UNITED STATES PATENT OFFICE.

PROCTOR O. COLE, OF GOULD, OKLAHOMA.

TRAIN-PIPE COUPLING.

1,090,453.

Specification of Letters Patent.

Patented Mar. 17, 1914.

Application filed May 7, 1912. Serial No. 695,704.

To all whom it may concern:

Be it known that I, PROCTOR O. COLE, citizen of the United States, residing at Gould, in the county of Harmon and State of Oklahoma, have invented certain new and useful Improvements in Train-Pipe Couplings, of which the following is a specification.

This invention relates to train-pipe couplings and has for its object the provision of simple mechanism whereby the train-pipes may be automatically coupled when the cars, upon which they are mounted, are coupled, and the ends of the fluid conduits brought into alinement and connected by an air-tight joint.

Secondary objects of the invention are to provide means whereby the heads of the train-pipe coupling will be guided into proper engagement automatically as the cars come together, and will be held together in such manner as to preserve the joint between the fluid-conveying passages or conduits, while yielding to the relative movement of the cars when the train is passing around a curve; also to provide means whereby the coupling heads will be held projected when uncoupled, so that they will be in position to properly engage the meeting coupling head when the cars are again brought together, and to provide means for connecting the improved coupling with the couplings now in use.

The invention is illustrated in the accompanying drawings, and will be hereinafter fully described, the novel features being subsequently pointed out in the appended claims.

In the drawings:—Figure 1 is a plan view of two coupling heads embodying my invention and showing the same engaged; Fig. 2 is a vertical longitudinal section of the same, taken on the central line 2—2 of Fig. 1; Fig. 3 is a horizontal central longitudinal section; Fig. 4 is a view showing the two heads in perspective and uncoupled. Fig. 5 is a detail transverse vertical section through the shank of the coupler head. Figs. 6, 7 and 8 are detail views of a valve employed to permit the coupling to be used with the ordinary coupling now in common use.

In carrying out my invention, I employ a coupling head, 1, having its front end cut away, as shown most clearly in Fig. 3, thereby providing the forwardly projecting arm 2 at one side of its central longitudinal line.

A passage 3 is formed through the coupling head for the flow of the fluid, and this passage is carried to a point near the front end of the arm 2, where it is turned laterally inward so as to open through the inner face of the said arm and provide a port 4.

A coupling head, of course, is mounted on each car, and when the heads are brought together, the forwardly extending arms 2 will overlap, as shown clearly in Figs. 1 and 3, and the ports 4 in the heads will be brought into alinement, as shown in Fig. 3, thereby establishing communication through the two heads, so that the fluid in the train-pipe may flow through all the cars of the train. The device is intended more specially for connecting the ends of the train-pipe controlling the brakes of the cars, but it will ordinarily be provided with three or more 75 passages or conduits, similar to the passage 3, so that the steam heating pipes and the signal pipes, as well as the air-brake train-pipes, will be automatically and simultaneously coupled.

In the inner side face of the arm 2, I form a recess 5 in which a gasket 6 is seated, and the gaskets of the opposed heads will fit together when the heads are coupled, as clearly shown in Fig. 3, and will be slightly 85 compressed, so as to pack the joint between the heads and prevent leakage. The inner edges of the gaskets project beyond the face of the heads, and to prevent the gaskets being damaged by being brought into sliding 90 contact, as the heads are coupled, I provide the projections or lugs 7 on the inner faces of the heads in advance and slightly above and below the gaskets, so that when the heads meet they will be deflected laterally to a 95 sufficient extent to permit the gaskets to clear each other, and then move in the plane of their axes to be brought into engagement. To effect this lateral movement of the heads, the inner faces of the arms 2 are beveled or 100 inclined outwardly and forwardly, as shown at 8, and these inclined or beveled faces meet as the heads are brought together and consequently force each head slightly away from the central longitudinal line of the 105 coupling until the lugs or projections 7 have cleared each other, whereupon the heads will be moved toward the central longitudinal line of the coupling to bring the gaskets together and cause the said lugs or projections 110 to engage behind each other, as shown most clearly in Fig. 1.

The forward end of the coupling head is beveled rearwardly in rear of the gasket at the same angle or degree of obliquity as the forwardly beveled surface 8 so as to accommodate the forwardly extending arm of an opposed head and permit the lateral movement by which the ports are caused to register.

To facilitate the lateral movement of the heads and to yieldingly hold them together, I employ the springs 9, one of which is secured to each head near the rear end thereof, and at the side opposite the projecting arm 2. The spring extends forwardly to a point about in line with the port 4, and its free end is equipped with a roller 10 adapted to ride upon the outer face of the forwardly projecting arm 2 of the opposed coupling head and engage a recess 11 in the outer side of said arm, so that the strength of the spring will be exercised to move the opposed head into engagement with the head to which the spring is secured and to hold the heads in engagement.

The roller 10 may be dispensed with, if preferred, and the out-turned end of the spring engaged directly by the coupling head, and to facilitate the movement of the coupling head under or past the end of the spring, a small beveled face 12 is provided at the forward end of the arm 2, which face extends rearwardly and outwardly. This face 12 engages a short surface extending forwardly and outwardly from the rearwardly beveled surface of the opposed head so that after the ports are in alinement the heads will be oppositely moved laterally to bring the ports together. Moreover, this particular construction limits the lateral movement imparted to the heads by the engaging oblique faces of the forwardly projecting arm and the opposed head, so that the strain upon the guide and the retaining spring will be relieved, and the heads cannot be moved laterally to such an extent in one direction to permit the gaskets to clear the projecting portions of the heads that the lateral movement in the opposite direction to bring the ports together cannot be effected.

The free ends of the springs 9 play through openings 13 formed in the guiding plates 14 which are secured to the sides of the heads, somewhat in advance of the rear ends of the springs 9, and are adapted to fit closely against the outer sides of the coupling heads, as shown in Fig. 3, to hold the heads in engagement. The free ends of these spring-plates 14 are flared somewhat outwardly, and at their upper and lower edges are provided with flanges 15 adapted to extend over the top and bottom of the opposed head. These springs thus serve as guides to effectually guide the heads together in the act of coupling, and the flanges

15 at the upper and lower edges of these springs will tend to limit the independent vertical movement of the heads, while, at the same time, permitting sufficient movement to accommodate differences in the heights of the cars.

To aid in guiding the heads together and to prevent vertical disengagement of the same, I provide on the top and the bottom of each coupling head, a keeper 16 which extends over the rear portion of the arm 2 and projects beyond the same, so that when the heads are coupled, the said keepers 16 will pass above and below the ends of the opposed projecting arms and thereby resist any tendency of said arms to vibrate vertically and thus throw the ports of the conduits or passages 3 out of alinement.

A cut-off valve 17 is mounted in the rear portion of each head, and this cut-off valve is operated by a rod 18 extending to the sides of the car, so that the valve may be adjusted without requiring the operator to pass between the cars. In rear of the said cut-off valve, the fluid passage 3 is carried laterally to emerge through the side of the head, and a hose or flexible coupling 19 is provided to connect the said passage with the train-pipe 20.

The coupling heads will be preferably supported by suitable hangers depending from the car couplings, and the rear ends of the heads will be slidably mounted in sills or beams 21 forming a part of the car frame, a spring 22 being fitted around the rear end of the head, between the said beam or sill and a shoulder on the head, so as to yieldingly hold the head forward and permit the head to cushion under the impact of coupling. A stop 23 of any convenient form will be provided on the rear extremity of the head to engage the beam or sill 21 and thereby prevent the spring 22 throwing the head from its supports. The head is provided in one side, in advance of the coiled spring 22, with a notch 24 in which the end of a spring 25 may engage when the heads are uncoupled, so that the head will be held in its projected position and no adjustment of the same will be needed when it is again desired to couple the cars.

To the hanger will be secured depending springs 26 having their lower ends bearing against the opposite sides of the stem or shank of the coupling head, so that the said head will be maintained in the central longitudinal line of the car, except during the slight interval of time when they are deflected laterally sufficiently to permit the coupling operation to be performed. I also provide in the passage 3, between the cut-off valve 17 and the free end of the coupling head, a valve 27 controlling a port or passage 28 opening through the bottom of the coupling head and equipped with a nipple 180

29 to permit the attachment of a short hose 30 adapted to be connected with a hose on an opposing or meeting car by means of the ordinary coupling now in common use. The 5 valve 27 is constructed with two ports or passages 31—32, and is also equipped with a handle 33 above the coupling head to permit its manipulation. When the handle 33 is arranged parallel with the coupling head, 10 the port 31 will be caused to align with the passage 3 at both sides of the valve, as shown in Fig. 7, whereby the air will be permitted to pass through the coupling head to the ports 4, and the transmission of the fluid effected through the engaged coupling heads. 15 Should the car, however, be coupled to a car not equipped with my improved coupling, the train-pipes will be coupled in the ordinary manner and the handle 33 then turned 20 diagonally of the coupling head, so that the air will then pass through the port 32 into the hose 30 and so into the train-pipe on the other car. The fluid may, of course, be entirely cut off by means of the valve 17 in 25 either instance.

It is thought the many advantages of my improved coupling will be readily understood and appreciated from the foregoing description, taken in connection with the accompanying drawings, and detailed mention of the same is deemed unnecessary.

Having thus described my invention, what I claim is:—

35 1. A train pipe coupling comprising a coupling head having a forwardly projecting arm at one side and a lateral port in the inner side wall of said arm, the portion of the side wall containing said port extending longitudinally of the coupling head and being provided with lateral projections in advance and above and below the port, the 40 front face of said arm extending obliquely

forwardly and outwardly and terminating in a short rearwardly and outwardly beveled face, and the coupling head having a front 45 rearwardly inclined face in rear of the port and a short forwardly and outwardly inclined face adapted to engage the inclined faces on the forwardly projecting arm of an opposed coupling head, a guide secured to 50 the rear end of the head at the side opposite the arm and resting flat against said side of the head and projecting forwardly beyond the said side to engage the projecting arm of an opposed head, keepers upon the top 55 and bottom of the head adjacent the oppositely inclined faces of the same and projecting forwardly beyond said faces and terminating short of the top and bottom of the adjacent guide, and a retaining spring secured to the rear end of the head and extending outwardly and forwardly from the head in spaced relation to the outer face of the guide, and then extending toward and projecting through the guide in rear of the 60 front end thereof to bear laterally upon the outer side of the projecting arm of an opposed head approximately in the plane of the lateral port.

2. In a train-pipe coupling, the combination with a fixed support, of a coupling head yieldably and slidably mounted in said support and provided with a notch in one side, and a spring secured to the support and having its free end adapted to engage said notch whereby to hold the coupling head in its forward position. 70

In testimony whereof I affix my signature in presence of two witnesses.
